**MOTOR DRIVEN HERMETICALLY SEALED
VARIABLE CAPACITOR**

**David D. Robertson, San Jose, Calif., assignor to Jennings
Radio Manufacturing Corporation, San Jose, Calif., a
corporation of Delaware**

Filed Nov. 7, 1962, Ser. No. 72,416

**Term of patent 14 years
(Cl. D26—1)**

Des. 201,358

PAGE 2

FIG. 1 is a perspective view of a motor driven hermetically sealed variable capacitor showing my new design;

FIG. 2 is a perspective view as seen from the other end;

FIG. 3 is a side elevational view;

FIG. 4 is an end elevational view as seen from the top of FIG. 3; and

FIG. 5 is an end elevational view as seen from the bottom of FIG. 3.

I claim:

The ornamental design for a motor driven hermetically sealed variable capacitor, as shown.
